UNITED STATES PATENT OFFICE.

FLORENCE M. KERLE AND WILLIAM KERLE, OF NEW YORK, N. Y.

DESIGN FOR A BABY-CARRIAGE BODY.

Application filed December 27, 1928. Serial No. 29,423. Term of patent 7 years.

To all whom it may concern:

Be it known that we, FLORENCE M. KERLE and WILLIAM KERLE, both citizens of the United States, and residents of the city of New York, borough of Manhattan, in the county of New York and State of New York, have invented the new, original, and ornamental Design for a Baby-Carriage Body, of which the following is a specification.

Reference is to be had to the accompanying drawing in which

Figure 1 is a view in side elevation of a

baby carriage body showing our new design, and

Fig. 2 is a top plan view thereof.

We claim:

The ornamental design for a baby carriage body as shown.

Signed at New York, in the county of New York, and State of New York this 20th day of December, A. D. 1928.

FLORENCE M. KERLE.
WILLIAM KERLE.
